UNITED STATES PATENT OFFICE.

OLIVER JUDD, OF CHERRY VALLEY, NEW YORK.

DOOR-LATCH.

Specification of Letters Patent No. 1,888, dated December 10, 1840.

To all whom it may concern:

Be it known that I, OLIVER JUDD, of Cherry Valley, in the county of Otsego and State of New York, have invented a new 5 and useful Improvement in the Construction of Door-Latches, by which improvement the inconvenience and danger in passing through the doorway from the projecting of the catch and the point of the latch beyond the wood 10 of the door and of the door-casing is done away.

The latches are made at less expense than the common ones now in use, are more durable, less liable to get out of repair, and per- 15 form their functions as well as the best.

To enable others to make use of my in- 20 vention, or improvement, I proceed to de- 25 scribe the construction and operation of the several parts, reference being had to the annexed drawings making a part of this 30 specification, in which—

Figure 1, is a side view of the latch, with 35 its joint B. Fig. 2, a side view of the trig- 40 ger, or lifter, and handle, and a diagonal 45 view of the two plates E, E, through which 50 it passes. Fig. 3, is a horizontal view of a 55 section of the trigger and handle where it 60 passes through one of the plates E, and is 65 confined in the same by its shoulders. Fig. 70 75 4, is a diagonal view of a knob handle and 80 of the plate E, to which it is attached. Fig. 85 5, is a side view of a trigger used with the 90 knob handle. Fig. 6, is the catch.

Fig. 1, A is the flat part and forward end 95 of the latch, being about five inches in 100 length, B is a round piece or plug of iron 105 or other metal, about one and one half of an 110 inch long and about five eighths of an inch 115 in diameter, this plug has a mortise or cham- 120 ber made in the center of it and extending 125 from the forward end about two thirds of 130 the length of the plug, of a suitable size 135 to receive the back end of the flat part of 140 the latch, this end of the latch is confined 145 in the said mortise or chamber of the plug 150 by a pin or rivet passing through the said 155 plug and the end of the latch, thus forming 160 a joint about the center of the plug.

This latch is inserted in the door, by bor- 165 ing a hole or mortise into the edge of the 170 same of a sufficient depth to receive the 175 length of the latch except about half of an 180 inch to take hold of the catch hereafter de- 185 scribed, the outward end of this hole or mor- 190

tise is enlarged so that the latch may rise in 55 the same sufficient to pass over the said 55 catch, while the back end is made to fit the 60 joint or plug and hold it fast; the forward 65 end of the latch is kept in its place by a 70 small plate C, with a mortise in the same 75 through which the latch passes, which plate 80 is fastened to the edge of the door.

Fig. 2 is the trigger, or lifter, and handle, 85 to raise the latch; this trigger passes through 90 the door directly under the latch, and is so 95 constructed at the ends D, D, as to form a 100 convenient handle on both sides of the door 105 to take hold of in opening and shutting the 110 same; this trigger and handle is kept in its 115 proper position, by two plates E, E, through 120 which it passes, (which plates are fastened 125 to the door, one on each side) and is kept 130 from sliding endwise through the door by 135 small projections or shoulders on the sides 140 of the same, near where it passes through 145 one of the said plates. Opposite the projec- 150 tion are the handle which is back of the 155 plate and within the door, is an indentation 160 or notch in the handle, so that by turning 165 the plate sidewise, in passing the handle 170 through the mortise, the plate will pass this 175 projection or shoulder, but when brought to 180 square with the handle as it will when fas- 185 tened to the door, the handle is kept from 190 moving endwise, either one way or the other 195 (see Fig. 3).

The handle is flat on the sides where it 200 passes through the mortise in the plates and 205 fills the same so as to prevent its turning 210 around, while the mortises are sufficiently 215 long to allow the said handle or trigger to 220 rise at either end so as to raise the latch 225 in opening the door.

Fig. 4, is a handle of a different construc- 230 tion and separate from the trigger or lifter; 235 this is a round knob or button, which is 240 connected with the plate E, above the mortise 245 by a neck or stem of about one inch in 250 length.

Fig. 5, is the trigger when the handle 255 (Fig. 4,) is used, this trigger passes through 260 the plates E, E, and the door, directly under 265 the latch, the same as the handle and trigger 270 before described, but is kept from sliding 275 endwise through the door, by the latch which 280 rests in a notch on the upperside of the said 285 trigger, this trigger is of sufficient length to 290 reach through the door and extend on each 295

side from the door, about three fourths of an inch, so as to be raised by the finger, at the same time taking hold of the knob or button which forms the handle, to open the door, this trigger is made flat on the sides where it passes through the plates E, E, and fills the mortises sufficient to keep it from turning around, but leaving a space in the mortises above so that it may be raised at 10 either end sufficiently to raise the latch.

Fig. 6, is the catch, this is made with a jog or catch on both sides, so that by reversing, it will answer for either side of the doorway, this is let into the wood, in the 15 rabbet made in the casing to receive the door.

What I claim as my invention and desire to secure by Letters Patent is—

1. The method of fastening the latch by having the joint of the latch in a plug which is driven into a hole made in the door, as 20 described.

2. The method of keeping the handle in place by means of the plates E, E, and the notches and shoulders on the handle and trigger, as described.

OLIVER JUDD.
